UNITED STATES PATENT OFFICE.

CHARLES WAHLERS, OF NEW YORK, ASSIGNOR TO ASHLEY M. HERRON, OF PALISADES, NEW YORK.

DESIGN FOR A JAR.

SPECIFICATION forming part of Design No. 22,157, dated January 24, 1893.

Application filed December 8, 1892. Serial No. 454,535. Term of patent 14 years.

To all whom it may concern:

Be it known that I, CHARLES WAHLERS, a citizen of the United States, residing in the city, county, and State of New York, have 5 originated a new Design for Jars, of which the following is a specification.

The leading features of my design for jars consist in the shape or outline of the jar-body and of its base and neck, as illustrated 10 in the accompanying drawings, in which

Figure I represents a side view, Fig. II, represents a plan or top view, and Fig. III, represents an end view of a jar embodying the design.

15 The letter A, indicates the jar-body, which is oval when viewed from the side and top, as in Figs. I and II, and circular when viewed

from the end thereof, as in Fig. III, the whole practically constituting an oval. The surface of this oval body A, is ornamented with 20 veins running in the direction of its length as shown, and with plain cavities b; the latter being at one end of the body. Combined with the oval body A, is a base C, and neck D, with plain surfaces, completing the jar. 25

What I claim and desire to secure by Letters Patent, is;

The design for a jar, substantially as shown and described.

CHARLES WAHLERS.
